Primary Examiner — Eric L Goodman*Assistant Examiner* — Sarah L Smith(57) **CLAIM**

The ornamental design for a motorized scooter, as shown and described.

DESCRIPTION

FIG. 1 is a front and top perspective view of a motorized scooter, showing our new design;

FIG. 2 is a rear and bottom perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof.

FIG. 9 is an enlarged view of a front wheel in FIG. 1;

FIG. 10 is an enlarged view of a rear wheel in FIG. 1;

FIG. 11 is an enlarged view of a handle in FIG. 1;

FIG. 12 is an enlarged view of a connector in FIG. 1;

FIG. 13 is an enlarged view of a front wheel in FIGS. 2; and,

FIG. 14 is an enlarged view of a rear wheel in FIG. 2.

The dashed broken lines in the figures illustrate portions of the article that form no part of the claimed design. The dash dot dash lines in FIGS. 1-2 and 9-14 are for the purpose of depicting the boundary lines of the enlarged view and form no part of the claim.
